UNITED STATES PATENT OFFICE.

DIEDRICH C. ADDICKS, OF BRONSON, MICHIGAN, ASSIGNOR OF ONE-HALF
TO GEORGE COOK, OF BURR OAK, MICHIGAN.

DEVICE FOR FORMING WIRE STAY-LOCKS.

SPECIFICATION forming part of Letters Patent No. 598,131, dated February 1, 1898.

Application filed June 10, 1897. Serial No. 640,211. (No model.)

To all whom it may concern:

Be it known that I, DIEDRICH C. ADDICKS, a citizen of the United States, residing at Bronson, in the county of Branch and State of Michigan, have invented a new and useful 5 Wire-Lock Former, of which the following is a specification.

This invention relates to a hand-machine for forming locks or fasteners from wire to be 10 used subsequently as means for securing crossing wires in the construction of wire fencing. The machine in its construction combines a gage to insure the wire being cut in uniform lengths, a cutter, means for bending 15 the wire into the required shape, and an ejector for removing the completed fastener or lock, the parts being disposed so as to economize space and secure lightness, combined with efficiency and durability.

20 For a full understanding of the merits and advantages of the invention reference is to be had to the accompanying drawings and the following description.

The improvement is susceptible of various 25 changes in the form, proportion, and the minor details of construction without departing from the principle or sacrificing any of the advantages thereof, and to a full disclosure of the invention an adaptation thereof is shown 30 in the accompanying drawings, in which—

Figure 1 is a perspective view of a machine embodying the essential features of this invention. Fig. 2 is a longitudinal section showing the machine applied to a support and 35 having a portion of the handle broken away, the dotted lines showing the position of the parts when the lock is released from the machine after being formed. Fig. 3 is a detail perspective view of the base portion of the 40 machine. Fig. 4 is a detail perspective view of the active end portion of the operating-lever. Fig. 5 is a detail view in elevation of the combined lock former and ejector. Fig. 6 is a detail view of a stay-lock.

45 Corresponding and like parts are referred to in the following description and indicated in the several views of the drawings by the same reference characters.

The machine comprises, essentially, three 50 parts—a base 1, a combined lock former and ejector 2, and an operating-lever 3, fulcrumed

to the base and constructed so as to actuate the operating parts in the manner presently to be described.

The base 1 is of oblong form and is provided with openings to receive fastenings or bolts, by means of which it is secured in a vertical position to a post or support 4, and is provided at its sides with ears 5 and at one end with parallel lugs 6. The central portion 55 of the base is elevated and has a longitudinal slot 7, and vertical grooves 8 in transverse alignment are formed in the walls of the slot 7 and extend in parallel relation to receive the side members of the lock when the latter 60 is in course of formation. The base has raised portions a short distance from the slot 7, which are notched at 9 to receive the wire preparatory to shaping the lock, said notches 65 serving to hold the end portions in position 70 while the initial bend is given thereto. A rib 10 projects along one ear 5 and constitutes a wall of the contiguous notch 9 and prevents the end of the wire from moving forward when giving the final shape thereto. A block 11 is 75 secured to the base at a point diagonally opposite the vertical rib 10 and is of best-quality tool-steel highly tempered and constitutes the fixed cutter and serves to prevent the rearward movement of the adjacent end of 80 the wire blank when forming it into the required shape. An opening 12 is formed in one of the ears 5 and is in line with the notches 9 and receives the wire when feeding it into the machine, the said wire being limited 85 in its movement by striking the inner face of the opposite ear and being properly positioned by entering the notches 9.

The combined lock former and ejector is of elbow form and is fulcrumed at or near the 90 elbow between the parallel lugs 6. The arm 13, projecting about at right angles from the plane of the base, is adapted to be engaged by the operating-lever 3 when thrown back, so as to move the arm 14 away from the base 95 and withdraw it from the slot 7, whereby the lock or fastener is withdrawn from the slot 7 and permitted to drop, thereby placing the machine in condition for forming another lock. The ejector is a finger or extension 15, 100 formed with the arm 14 and disposed to project across the plane of the grooves 8 and the

wire blank fed between the arm 14 and the ejector 15, so as to engage with the closed or folded end of the lock and disengage it from the machine when the lever 3 is thrown backward. The edge of the arm 14 facing the base 1 is rounded to give a corresponding form to the closed end of the lock. The operating-lever 3 is fulcrumed between the ears 5 upon a pin supported in openings 10 formed therein and is provided at its active end with a cam 16 and a cutter 17, the latter being preferably a tempered-steel block fastened thereto and adapted to coöperate with the cutter 11 for severing the wire in the formation of the lock. The cam 16 operates over the raised portion of the base having the slot 7 and between the elevated parts having the notches 9 and is intended to engage with the arm 14 and move it into the slot 7, thereby 20 folding the wire blank extending across the slot, while at the same time the side members of the staple or lock are slightly bent, thereby facilitating the application of the lock to the fence when connecting the wires at the point 25 of crossing. As the blank is folding the end portions are drawn into the grooves 8 and project at right angles from the elevated portion of the base, and their terminal ends are engaged by the parts of the cam 16 projecting 30 beyond the sides of the arm 14 and are deflected, thereby giving to the finished staple or lock the form presented in Fig. 6. In this connection it must be remembered that the end portions of the staple or lock are longer 35 than the width of the arm 14 opposite the grooves 8. Consequently they are engaged by the cam 16 simultaneously with its finishing action upon the arm 14.

The wire from which the locks or fasteners 40 are to be formed may be of suitable gage and is fed to the machine through the opening 12 and is shaped by moving the operating-lever so as to depress the arm 14 of the part 2. During the first part of the movement of the 45 lever 3 the wire is severed by the coöoperating cutters 11 and 17, and a continued movement of the lever depresses the arm 14 and bends the wire into the form of a staple, and the final movement bends the end portions of the 50 side members comprising the staple, as clearly indicated in Fig. 6. The lever is now thrown backward and, engaging with the arm 13 of the part 2, withdraws the arm 14 from the slot 7 and releases the lock, which falls from the machine, thereby admitting of a repetition 55 of the operation just described in the formation of subsequent locks or fasteners.

Having thus described the invention, what is claimed as new is—

60 1. In a machine for forming stay-locks, the combination of a base having a slot and grooves in the sides of the slot, an elbow-shaped former having an arm adapted to enter the said slot, and an operating-lever having a cam portion to engage with one arm of the said former to press it into the aforesaid slot to shape the lock, and adapted when thrown

back to engage with the opposite arm of the former to withdraw the other arm from the slot, substantially as set forth. 70

2. In a machine for forming stay-locks or fasteners, the combination of a base, a combined lock former and ejector coöoperating with the base for shaping the wire blank into the required form, and an operating-lever for 75 moving the combined lock former and ejector positively in each direction to form the lock and disengage it from the machine when completed, substantially as set forth.

3. In a machine for constructing stay-locks 80 for wire fencing, the combination of a base having a slot and grooves at the sides of the slot communicating therewith, a pivoted arm to operate in the said slot and bearing a finger or extension to operate across the plane of 85 the said grooves, and means for positively moving the pivoted arm in each direction to form the lock and disengage it from the machine when completed, substantially as set forth. 90

4. In a machine for forming stay-locks, the combination of a base having a slotted portion, and having notched parts at each side of the slot, the walls of the slot being grooved, a pivoted arm bearing a finger or extension 95 forming an ejector and adapted to operate in the aforesaid slot and across the plane of the said grooves, and means for positively actuating the pivoted arm in each direction, substantially as specified. 100

5. In a machine for forming stay-locks, the combination of a slotted base having grooves in the walls of the slot, a former adapted to operate in the said slot, and a lever having a cam portion for pressing the former into the 105 said slot to shape the lock and projecting beyond the sides of the former to engage with and bend the side members of the lock in one continuous movement, substantially as set forth. 110

6. In a machine for forming stay-locks, the combination of a slotted base, a fixed cutter at one side of the slot, a pivoted former to operate in the slot, and an operating-lever provided with a cam portion for actuating the 115 former and bearing a cutter to coöperate with the cutter of the base, substantially as set forth.

7. In a machine for forming stay-locks, the combination of a slotted base having notched 120 portions at each side of the slot and a part at one side formed with an opening in line with the notches, a fixed cutter applied to the base, a pivoted former for working in the slot, and an operating-lever having a cam portion for 125 actuating the pivoted former and bearing a cutter to coöperate with the cutter of the base, substantially as set forth.

8. The herein-described hand-machine for forming stay-locks from wire, comprising a 130 slotted base having notched portions at each side of the slot and side ears, one of the ears having an opening in line with the notched portions, a cutter applied to the base, an elbow-

former provided with an ejector to operate in the slot of the base, and an operating-lever fulcrumed between the said ears and provided with a cam portion to actuate the former, and having a cutter to coöperate with the cutter of the base, and adapted when thrown back to engage with the elbow-former and withdraw the arm bearing the ejector from the slotted portion of the base, substantially in

the manner set forth for the purpose described.

In testimony that I claim the foregoing as my own I have hereto affixed my signature in the presence of two witnesses.

DIEDRICH C. ADDICKS.
